Inventor.

UNITED STATES PATENT OFFICE.

KARL ERICH ARNDT, OF BERLIN, GERMANY.

MEANS FOR DRYING CIGARS AND THE LIKE.

Application filed November 7, 1927, Serial No. 231,757, and in Germany November 5, 1926.

This invention refers broadly to the art of drying smokers' supplies with a view of thereby increasing the palatability, taste and combustibility of tobacco products, and the invention among other possibilities of application is particularly applied to the drying of the tobacco, cigars, cigarettes, pipes and the like before their consumption or utilization. In all the embodiments in accordance with my invention I make use of the combination of a heating source, such as a lamp with supporting means on which is placed a cigar or cigarette to be dried, and operating in such a manner that the cigar or cigarette is adjustably, that is to say, displaceably, and rotatably held with its ignition-extremity within the operative reach of the source of heating, a flame for instance. Among other objects the invention is intended to provide means of producing a slow and uniformly thorough heating of the ignition-end of the cigar or cigarette and in case of a cigar where the mouth end of which has been cut off, or this has been perforated or notched. By this means a preliminary heating of the entire cigar is produced through the action of the hot gases which are passed through the cigar from its heated end. This results in increasing the palatability and the wholesomeness of the smoke.

The invention will be more fully described by reference to the accompanying drawing, in which Figs. 1 to 4 show different modifications of means embodying the principles of my invention in elevation and perspective view respectively.

In the form of construction according to Figure 1, the tank or reservoir of the roasting lamp 1, a small spirit-lamp for instance, is provided with a supporting member 2 which may be detachably arranged, and which is bent or shaped in such a manner, as to present an arcuate or vaulted or trough-shaped rest 3 for the cigar 4 or the like. Upon this supporting bracket or rest 3 the cigar or the like 4 may easily be manipulated, so as to have its ignition-end within operative reach of the heat of the flame of the lamp, and it may also be uniformly turned, if desired, by manipulating the cigar from the other, previously cut-off extremity.

Opposite to the holders 2, 3, and connected to the part 2 thereof, a holder 5 for the casing 6 of a match-box 7 is provided.

As indicated by dotted lines in the drawing the burner-top of the lamp may be provided with a cap 1^a, slid over the burner and adapted for extinguishing the flame.

The modification according to Figure 2 which is shown partly in elevation and partly in section is particularly adapted as a portable travelling and pocket-implement; it comprises a fuel reservoir 1 with a closing lid 8 which may be hinged at 9 to the reservoir, and carries the rests or holders 12 for the cigar or the like, these holders being pivoted to the end 8 and adapted to be swung into the upright position. As a supporting foot for the lid 8 in the swung-out operative position thereof the leg 10 may be used which is bent downwards from the hinge 11. The tight closing of the burner-pipe may be secured for instance by the rubber cushion 8^a in the form of an annular disk secured on the lid 8.

In the modified construction according to Figure 3 the lamp 1 serving as the heating source is provided with a holding or carrying rod or bracket 2, formed for instance from wire which is easily removable and the horizontal portion 2^a thereof is displaceable by means of clamps 2^c or by means of pins or the like and is thus adjustably connected to the supporting bar 2^b which carries the internally screw-threaded member 13 which has the screw thread spindle or shaft 14 mounted therein. This spindle or shaft 14 carries a preferably spring-clamping member 16 for the cigar to be heated as is shown at 4; and at the other end of the spindle is provided a hand wheel 15 which may be replaced, if desired, by a small crank or the like for the purpose of advancing the cigar towards the flame, and also for the turning of the cigar 4 with relation to the heating flame, the other end of the cigar loosely rests on a forked holder or rest 12. The coarse adjustment may be quickly and easily obtained by displacing the rods or bars 2^a, 2^b.

In the modification shown in Figure 4 of the drawing a spring operated clockwork or motor is provided for reciprocating rotating of the holder 16 for the cigar 4 within operative reach of the lamp-flame. Thereafter said clockwork or motor is placed in a casing 20 mounted upon a post 19, and is adapted to be wound up and started at 21. On the end of shaft 14 of the spring motor or clockwork is slidably

mounted the spindle 13^a which is provided with connected right-and-left hand threads on its periphery. The said screw-spindle carries the holder 16 for the cigar 4 at its 5 other end. A member 22 fixed to the motor has a downwardly extending end engaging in the right and left hand threads on the spindle 13^a. When the holder for the cigar is rotated by the motor, the engagement of 10 the member 22 in the threads gives to the holder a back-and-fourth movement towards and from the flame 1^a. The clockwork is preferably so arranged that, after having been wound up, it may be started and ar- 15 rested at any time in the discretion of the operator. For the purpose of adjustment, particularly for cigars or the like of different lengths, the clockwork 19, 20 and respectively the lamp 1 or both of these 20 members may be displaceably mounted upon the common base plate 18.

As heating sources for the heating of the cigar, cigarette or the like in accordance with the invention I may also employ electric heating devices. Instead of the driving 25 by clockwork 19, 20 electromotive driving means may be used which may be driven for instance by a dry-battery or the like.

The implements according to this invention 30 are also very well suited for use as advertising means, thus for instance for cigar- and cigarettes-manufacturers, the advertising matter being applied to any suitable parts of the implement, as for instance on the lamp or the carrying support by means of a plate-shaped enlargement of 35 a portion of the holder 2 in Figure 1.

It should be understood that the invention 40 is not restricted to the particular forms of embodiment herein shown by way of exemplification only, but other modifications and changes of construction are possible within the spirit and scope of the invention, as defined in the appended claims.

45 I claim:

1. In a device of the kind described, a 50 heating source, supporting means on said source, and longitudinally adjustable and extensible sections on said supporting means, and carrying and turning means on said sec- tions.

2. In a device of the kind described in combination, a heating source, holding

means laterally disposed on said heating 55 source, and comprising a plurality of relatively displaceable sections and adapted to move the article to be treated into the operative position.

3. In a device for drying cigars, cigarettes and the like, in combination, a heating 60 source, laterally and upwardly extending holding means for cigars and the like connected to said heating source, and means to adjust the holding means and the heating source with relation to each other to adapt the device to varying lengths of cigars and to position the cigar at varying distances from the heating source, said holding means including means to reciprocate the cigar or the like to and from the flame. 70

4. In a device for drying cigars, cigarettes and the like, in combination, a heating source, laterally and upwardly extending holding means for cigars and the like connected to said heating source, and means to adjust the holding means and the heating source with relation to each other to adapt the device to varying lengths of cigars and to position the cigar at varying distances from the heating source, said holding means 75 comprising means to reciprocate the cigar or the like to and from the flame and to rotate the cigar about its longitudinal axis.

5. In a device for drying cigars, cigarettes and the like, in combination, a heating 85 source, laterally and upwardly extending holding means for cigars and the like connected to said heating source, and means to adjust the holding means and the heating source with relation to each other to adapt 90 the device to varying lengths of cigars and to position the cigar at varying distances from the heating source, said holding means comprising means to reciprocate the cigar or the like to and from the flame and to 95 rotate the cigar about its longitudinal axis, said reciprocating and rotating means comprising a clamp for gripping an end of the cigar, a screw threaded shaft on one end of which the clamp is secured, a screw threaded 100 nut formed on said support and with which the shaft engages and hand operated means secured to the other end of the said shaft.

In testimony whereof I affix my signature.

KARL ERICH ARNDT.
